Des. 184,555
Patented Mar. 10, 1959

184,555

FLEXIBLE SUNGLASS FRAME OR THE LIKE

Jack Bloch, Leominster, Mass., assignor to Foster Grant Co., Inc., Leominster, Mass., a corporation of Delaware

Application February 3, 1958, Serial No. 49,491

Term of patent 14 years

(Cl. D57—1)

Fig. 1 is a front elevational view of a flexible sunglass frame or the like, spread out flat, showing my new design; and

Fig. 2 is a bottom plan view thereof. The rear not shown is substantially plain.

I claim:

The ornamental design for a flexible sunglass frame or the like, substantially as shown and described.
